(57) **CLAIM**

I claim the ornamental design for a double fender, as shown and described herein.

DESCRIPTION

FIG. 1 is a top, front and side perspective view of a double fender showing my new design;

FIG. 2 is a side elevation view thereof;

FIG. 3 is a top and front perspective view thereof;

FIG. 4 is a top, rear and opposite side perspective view thereof;
FIG. 5 is an enlarged fragmentary inner detail perspective view taken along detail circular line A in FIG. 4; and,
FIG. 6 is an opposite side elevation view thereof.
